(57) **CLAIM**

The ornamental design for a snap button, as shown and described.

DESCRIPTION

FIG. 1 is a side view of the snap button according to my new design in an assembled position, with all other side views being identical;

FIG. 2 is a top view thereof;

FIG. 3 is a cross-sectional view along lines 3-3 of FIG. 2; FIG. 4 is a bottom view thereof;

FIG. 5 is a top and side perspective view thereof; FIG. 6 is a bottom and side perspective view thereof; FIG. 7 is a side view of the female portion of the snap button, with all other side views being identical and with the male portion being removed for ease of illustration;

FIG. 8 is a top and side perspective view of the female portion of FIG. 7;

FIG. 9 is a cross-sectional view along lines 9-9 of FIG. 8; FIG. 10 is a bottom and side perspective view of the female portion of FIG. 7;

FIG. 11 is a bottom view of the female portion of FIG. 7; FIG. 12 is a side view of the male portion of the snap button, with all other side views being identical, and with the female portion removed for ease of illustration;

FIG. 13 is top view of the male portion of FIG. 12;

FIG. 14 is a cross-sectional view along lines 14-14 of FIG. 13;

FIG. 15 is a bottom view of the male portion of FIG. 12; FIG. 16 is a top and side perspective view of the male portion of FIG. 12;

FIG. 17 is a bottom and side perspective view of the male portion of FIG. 12;

FIG. 18 is a side view of the snap button as used to connect two layers of fabric; and,

FIG. 19 is a cross-sectional view of the snap button as shown in FIG. 18.

The elements shown in broken lines in FIGS. 18 and 19 show environmental structure only and form no part of the claimed design.

1 Claim, 6 Drawing Sheets
